UNITED STATES PATENT OFFICE.

WESLEY CLINE, OF EDMONTON, ALBERTA, CANADA.

AUTOMOBILE SIGNAL.

1,414,981.

Specification of Letters Patent. Patented May 2, 1922.

Application filed September 10, 1921. Serial No. 499,642.

To all whom it may concern:

Be it known that I, WESLEY CLINE, a subject of the King of Great Britain, and residing at the city of Edmonton, in the 5 Province of Alberta, Dominion of Canada, have invented a new and useful Improvement in Automobile Signals, of which the following is the specification.

My invention relates to improvements in 10 automobile signals and is for the purpose of indicating to the car following, the intention of the car in front, to turn off in either direction and would be of a special advantage to a closed car where it is impossible for a 15 driver to put his arm out.

The device consists of two arms enclosed 20 in a metal casing, one at either side, and is attached to the car below the windshield. A hand is formed at the end of each arm, having folding fingers, which spread out 25 when the arm is projected and fold inward when the arm is pulled back into the casing. The second and third fingers are fashioned out of the end of the strips forming the arm. 30 The little finger, index finger and thumb are made of separate pieces and fit into spaces formed by the three strips which go to make up the arm. These strips are held apart by fillers placed at the tips of the second and 35 third fingers and by strips fastened across the top and bottom just back of the movable fingers.

The little finger, index finger and thumb are pivoted in the spaces between the strips 40 forming the arm and have tension springs attached to the inner ends of same and the other ends of the springs connected to the centre strip forming part of the arm, to keep the fingers spread out when the arm is exposed. When the arm is pulled in, the movable fingers are forced into the spaces between the strips forming the arm by guide pieces at the upper and lower edges of the casing. The centre strip of the arm has a 45 portion cut out just back of the inner end of the fingers, to allow the springs to fit in and to form an edge to attach the other ends of springs to.

The casing enclosing the arms is made in 50 two lengths, with a sleeve or holder in the centre, to allow the casing to be lengthened or shortened to suit the width of the car to which it is to be attached. Each length of casing is made in four pieces, the top and 55 bottom being curved in the form of a half circle, with the ends being bent back to form

grooves, into which the side strips slide. Runners in the form of U-shaped strips are placed at the top and bottom, inside the casing, to act as guides for the arms and to ensure easy operation. Slots are formed in the outer strips facing the driver, one for each arm, and an operating rod, which is attached to the centre strip of the arms, pass through 60 said slots and turn at right angles and run 65 along the face of the casing, slightly beyond the centre of the device, to allow of them being easily handled by the driver of the car, without having to reach too far to either side. 70

The device is suitably attached to the car by screws or brackets.

When the device is used with a closed car, small brackets with guide pulleys are placed 75 at either side where the openings are made in the car for the arms to pass through, for the purpose of guiding the arms out and in. The brackets are attached to the ends of the device itself when used with an open car.

I attain these objects by means of the 80 mechanism as shown in the accompanying drawings, in which:

Fig. 1 is a front view of the device showing one half in section and the other half in full; one arm projecting, showing fingers extended when acting as a signal, and the other arm drawn back into the casing with the fingers folded together. 85

Fig. 2 is an enlarged detail of the arm showing the movable fingers pivoted to the 90 arm and attached by springs to the centre strip, which has a portion cut away to receive the springs.

Fig. 3 is a top view of the arm, showing the position of the three strips forming the 95 arm with the spaces in between and the fingers fitting therein and the springs attaching the fingers to the centre strip.

Fig. 4 is an end view of the device showing the position of the arm inside the casing. 100

Fig. 5 is a front view of the bracket which is affixed to the car at the openings through which the arms pass to guide them in passing out or in.

Similar letters refer to similar parts 105 throughout the various views.

A is the device which is a metal casing made in two lengths and held together in the centre by the sleeve B, which is for the purpose of allowing the device to be lengthened or shortened to suit the width of the car. Each length of the device A is made in 110

four pieces, the top C and bottom D are semi-circular in form with the lower edges turned up forming grooves *a* and *b*. The sides E and F are flat strips of metal having 5 their edges turned back forming grooves *c* and *d*, said grooves engaging with the grooves *a* and *b* of the top and bottom strips C and D, allowing the sides to slide into place.

10 This design allows the whole device to be easily taken apart.

Inside the casing are the two signal arms G, one to operate on either side of the car. U-shaped strips H are affixed inside the top 15 and bottom C and D of the casing, to act as runners and guides for the arms G. At the end of each arm is a hand I. The second and third fingers *e* and *f* of the hand I are formed at the end of the strips composing 20 the arms G. The little finger *g*, the index finger *h* and the thumb *j* are made in separate pieces and are pivoted in the spaces formed between the three strips forming the arm G. The fingers *h* and *g* slide into the 25 same space between two strips of the arm G, only from opposite sides, and a small guiding strip *k* is attached to the upper edge of the centre strip J, and the lower end of the strip overlaps a portion of finger *g* to 30 guide same into place and to keep the two fingers *g* and *h* from catching or interfering with one another.

When the arm G is exposed, the fingers 35 spread in the form of an open hand and are held in that position by springs K attached to the pivoted ends of the fingers, which are so shaped and pivoted that the pull of the springs keep them spread out. The centre strip J of the arm G has a portion cut

out to allow space for the springs K, which 40 are also attached to the centre strip at the end of the opening. The centre strip J of the arm G is slightly longer than the two outer strips and has a rod L attached to this projection and held in place by nut l. The 45 rod L then passes through slot M in the side strip E and turns at right angles and projects along the face of the side strip E a sufficient distance to make it convenient for the driver of the car to operate the signal 50 without reaching too far in either direction. The slot M is of sufficient length to allow the rod L to slide the necessary distance to extend the signal arm to its full length.

N is a bracket with guiding pulleys m 55 and n and is attached to the opening made in a closed car, to guide the arms out and in. If used on an open car, the guide pulleys are attached to the ends of the casing.

What I claim as my invention is: 60

In a vehicle signal, a case and an expanding signal formed of an arm portion and a hand portion the former being formed of a strip of material terminating in two fingers of the hand and of other strips spaced to 65 form finger slots and spring slots, fingers in said slots and springs holding said fingers to their expanded position and a crank operating mechanism adapted to retire said hand in said case and coincidentally close in 70 the fingers to their slots.

Signed at the city of Edmonton, this 26th day of August, 1921.

WESLEY CLINE. [L.S.]

In the presence of—

C. MEDLEY,
D. SANDILANDS.
